UNITED STATES PATENT OFFICE.

WILLIAM F. HELMOND, OF HARTFORD, CONNECTICUT, ASSIGNOR TO
UNDERWOOD TYPEWRITER COMPANY, OF NEW YORK, N. Y., A COR-
PORATION OF NEW JERSEY.

TYPE-WRITING MACHINE.

No. 848,649.

Specification of Letters Patent.

Patented April 2, 1907.

Application filed December 28, 1906. Serial No. 349,772. (Model.)

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to type-writing machines in which type-bars are pivoted and guided in radially-slotted segments to strike forwardly and rearwardly.

The type-bar-guiding slots are usually cut upon the periphery of the cast-iron segment, 15 which is usually very much thickened at the slotted portion in order to afford extensive side bearings for the type-bars. The segments are usually made of cast-iron and the slots are usually cut by means of revolving 20 saws, and it has been found in practice that the operation of sawing the slots causes the segments to spring out of shape. In such machines it is found necessary for the type-bars to fit very accurately indeed in the slots; 25 but owing to the variations in the slot-openings, due to the springing of the segment aforesaid, it is found that the type-bars if all finished alike will not fit properly in the slots, as the latter vary in width in an ungovernable manner. It therefore becomes necessary to fit the type-bars individually to the 30 slots, which requires highly-skilled labor and involves great expense.

One of the objects of my invention is to 35 minimize or eliminate the springing of the segment, to the end that the stops may be more even in the completed segment and the fitting of type-bars thereto rendered less expensive.

My invention although adapted for certain 40 other machines is especially intended for use on the Underwood type-writer machine and is illustrated in connection with well-known parts of said machine. Heretofore the Underwood segment has not only been 45 thickened at the slotted portion, as already explained, but has also been formed above the slots with a rib projecting from the front face and serving as an anvil for the type-bars to strike against near their hub portions, and 50 thereby to secure nicety of their type impressions on the paper. The type-bars have been cranked around said slotted portion of the segment in order to enable them to con-

tact with said rib or anvil. This cranking is objectionable, in that it tends to reduce 55 the torsion-resisting quality of the bar. I thicken the segment not only at the slotted portion thereof, but also up to and including the anvil portion thereof. In other words, I provide around the periphery of the segment 60 a single broad thick rib. A large portion of this rib is uncut, so that it forms a solid body capable of withstanding the stress set up in the models by action of the slot-guiding saws, and hence the spring of the segment is 65 largely reduced or eliminated and the slots do not change by reason of the springing of the segment, as heretofore. Moreover, cranking of the type-bar is avoided, since each type-bar when in printing position after 70 emerging from the slot extends directly up the front side of the rib and contacts with the paper edge thereof which corresponds to the anvil heretofore implied and from said anvil extends forwardly and rearwardly to the 75 type-bar ends. The objectionable cranking heretofore referred to at the hub of the type-bar is avoided and better type impressions are attained, more particularly in the case of the type-bars at the sides of the system. 80 Said rib forms the larger portion of the bulk of the segment, and owing to the slots being cut wholly on its under side no liability is experienced of the entrance of dust and dirt into the slots. Heretofore in said machine 85 a curved slot has been formed in the rear face of the segment, and this slot has been occupied by a curved universal bar. One of the features of my improvements consists in eliminating said slot, thus leaving the rear 90 face of the segment plane, (except for the slot which receives the type-bar fulcrum-wire,) and hence less liable to catch dirt falling from the platen, while a broader or deeper bearing is afforded for the type-bars, 95 so that the liability of the twisting of the latter is minimized.

Other features and advantages will hereinafter appear.

In the accompanying drawings, Figure 1 100 is a sectional side elevation of the portion of an Underwood type-writing machine provided with my improvements, the type-bar being shown in printing position. Fig. 2 is a front elevation, and Fig. 3 a rear elevation, 105 of the type-bar segment.

Springy type-bars 1 are guided in radial slots 2 in an upright segment 3 and hung upon a curved fulcrum-wire 4 to strike rearwardly against the front side of a platen 5. The segment, which is of cast-iron, is formed along its lower or outer edge with a broad rib or thickened portion 6, projecting from the front face of the segment, a type-guide 7 of the usual construction being secured upon the front of the segment above said rib. The guiding-slots 2 are cut entirely through the rib 6 from front to rear. The type-bars strike upon the upper edge or border of said rib, their upper portions springing rearwardly to strike the platen in a known manner. Preferably the anvil portion of the rib has a slightly-raised segmental surface 8, which can be readily "finished" or trued up for the type-bars to strike upon, and the latter may, if desired, have projections 9 to strike upon the anvil.

Each type-bar when in printing position extends forwardly and upwardly from the pivot 4 to a point a little in the front of the rib 6 and extends thence directly upward with a slight rearward inclination to its type-carrying end, as seen at Fig. 1; the types being designated as 10. This form of bar possesses great rigidity and may be depended upon to produce clear impressions and will stand harder use than the cranked bars already referred to.

From the lower rear portion of the segment extends a segmental flange 11, sloping downwardly and rearwardly, both to stiffen the segment and to prevent droppings from the platen entering the slots on the rear side of the segment, said rib 11 projecting rearwardly over the portions 12 of the type-bar hubs which project rearwardly from the segment. The slots at their upper ends may extend forwardly and upwardly through the front of the rib, as at 13, and the type-bars may have at their hub portions the corresponding upward and forward inclination, as at 14, thus tending to give the bar a maximum strength by reducing the length of that unsupported portion of the bar which extends from the slot up to the type. The slots 2 preferably extend rearwardly through the lower portion of the rib 11, thus tending to give the type-bars a more extensive support from front to rear, and for the same purpose the rib 6 may be made thicker below the flange 11, as illustrated at 6^a. The rear face 6^a of the rib 6 is preferably plane and vertical, with the exception of the curved slot 15, which is occupied by the pivot-wire 4.

The universal bar 16, forming part of the carriage-feeding and ribbon-operating mechanism, lies normally against the rear face 6^a of the segment and is pressed rearwardly by heels 17, formed on the type-bars and projecting back from said face 6^a when the type-bars are in printing positions, as at Fig. 1.

The front face of the rib 6 is approximately plane and vertical from the top of the anvil portion thereof to the top of the slot portion thereof.

The type-bars are operated by the usual bell-cranks or levers 18, having pins 19 detachably engaged to long slots 20, which are formed in the lower ends of the bars nearly radial to the fulcrum-wire 4. Said slot 20 terminates at its upper end, Fig. 1, in a short slot 21, which directly engages the fulcrum-wire 4. The slot 21 is cut substantially concentric with the type or with the point 22 at which the types strike the platen, so that if by reason of faulty action of the type-bar it moves rearwardly at its hub portion while the type is moving to the printing-point the type will still print in alignment, since the hub can swing back the length of the slot 21 without disturbing the alignment or longitudinal position of the type-bar. It will be seen that the upper and lower edges of the slot 21 are cut upon the arcs 23 and 24, struck from point 22. As usual, the slots in the type-bar are open, as at 25, for ready detachment from the wire 4.

Having thus described my invention, I claim:

1. In a type-writing machine, the combination with a set of type-bars, of an upright segment having radial guiding-slots in which the type-bars are hung on a curved pivot-wire; said segment being formed with a broad rib or thickened portion projecting from its front face along its lower edge, the type-bar-guiding slots being cut through only the under side of said rib, the top of said rib being broad and unslotted, and the type-bars constructed to strike rearwardly against only the upper edge or border of said rib, to permit the types to spring to the platen.

2. In a type-writing machine, the combination with a set of type-bars, of an upright segment having radial guiding-slots in which the type-bars are hung on a curved pivot-wire; said segment being formed with a broad rib or thickened portion projecting from its front face along its lower edge, the type-bar-guiding slots being cut through only the under side of said rib, the top of said rib being broad and unslotted, and the type-bars constructed to strike rearwardly against only the upper edge or border of said rib, to permit the types to spring to the platen, the type-bars being formed with projections to contact with the rib.

3. In a type-writing machine, the combination with a set of type-bars, of an upright segment having radial guiding-slots in which the type-bars are hung on a curved pivot-wire; said segment being formed with a broad rib or thickened portion projecting from its front face along its lower edge, the type-bar-guiding slots being cut through only the under side of said rib, the top of said rib

being broad and unslotted, and the type-bars constructed to strike rearwardly against only the upper edge or border of said rib, to permit the types to spring to the platen, the type-bars formed with projections to contact with the rib, and the latter having a slightly-raised surface to be struck by said projections.

4. In a type-writing machine, the combination with a set of rearwardly-striking type-bars, of an upright segment having radial guiding-slots in which the type-bars are hung on a curved pivot-wire; said segment being formed with a broad rib or thickened portion projecting from its front face along its lower edge, the type-bar-guiding slots being cut through only the under side of said rib leaving a broad portion of the rib above the stop, each type-bar when in printing position extending forwardly from its pivot to clear said rib, and thence straight upward with a slight rearward inclination to its type-carrying end, and constructed to strike rearwardly, at a point well above the slot, against only the upper edge or border of said rib.

5. In a type-writing machine, the combination with a set of rearwardly-striking type-bars, of an upright segment having radial guiding-slots in which the type-bars are hung on a curved pivot-wire; said segment being formed with a broad rib or thickened portion projecting from its front face along its lower edge, the type-bar-guiding slots being cut through only the under side of said rib leaving a broad portion of the rib above the stop, each type-bar when in printing position extending forwardly from its pivot to clear said rib, and thence straight upward with a slight rearward inclination to its type-carrying end, and constructed to strike rearwardly, at a point well above the slot, against only the upper edge or border of said rib; said segment having projecting from its rear lower portion a segmental flange extending back over portions of the type-bar hubs which project rearwardly from the segment, and the segment being thickened on its rear side below said flange, to afford extensive bearings for the type-bars.

6. In a type-writing machine, the combination with a set of rearwardly-striking type-bars, of an upright segment having radial guiding-slots in which the type-bars are hung on a curved pivot-wire; said segment being formed with a broad rib or thickened portion projecting from its front face along its lower edge, the type-bar-guiding slots being cut through the lower portion of said rib, and the type-bars constructed to strike upon the upper edge or border of said rib, each type-bar when in printing position extending forwardly from its pivot to clear said rib, and thence directly upward with a slight rearward inclination to its type-carrying end; said segment having projecting from its rear lower portion a segmental flange extending back

over portions of the type-bar hubs which project rearwardly from the segment; a curved universal bar directly in rear of the segment and below the flange and operable by heels on the type-bars, which are constructed to project rearwardly from the rear face of the segment when the type-bars are in printing position; said segment having on its rear face below said flange a single curved recess, and said pivot-wire occupying said recess.

7. In a type-writing machine, the combination with a set of rearwardly-striking type-bars, of an upright segment having radial guiding-slots in which the type-bars are hung on a curved pivot-wire; said segment being formed with a broad rib or thickened portion projecting from its front face along its lower edge, the type-bar-guiding slots being cut through the lower portion of said rib, and the type-bars constructed to strike upon the upper edge or border of said rib, each type-bar when in printing position extending forwardly from its pivot to clear said rib, and thence directly upward with a slight rearward inclination to its type-carrying end; said segment having projecting from its rear lower portion a segmental flange extending back over portions of the type-bar hubs which project rearwardly from the segment; the type-bar-guiding slots extending through the lower portion of said flange, thence upwardly and forwardly through the front of the rib, and the type-bars having at their hub ends a corresponding upward and forward inclination.

8. In a type-writing machine, the combination with a set of rearwardly-striking type-bars, of an upright segment having radial guiding-slots in which the type-bars are hung on a curved pivot-wire; said segment being formed with a broad rib or thickened portion projecting from its front face along its lower edge, the type-bar-guiding slots being cut through the lower portion of said rib, and the type-bars constructed to strike upon the upper edge or border of said rib, each type-bar when in printing position extending forwardly from its pivot to clear said rib, and thence directly upward with a slight rearward inclination to its type-carrying end; said segment having projecting from its rear lower portion a segmental flange extending back over portions of the type-bar hubs which project rearwardly from the segment; the type-bar-guiding slots extending through the lower portion of said flange, thence upwardly and forwardly through the front of the rib, and the type-bars having at their hub ends a corresponding upward and forward inclination, the front face of said rib being approximately vertical from the top of the anvil portion to the top of the slot portion thereof.

9. In a type-writing machine, the combination with a segment having radial slots, of a set of type-carrying bars guided in the

slots and mounted on a curved pivot-wire, the type-bars having each a long slot engaged by an operating-pin, and said slot terminating at its inner end in a short wire-engaging slot at an angle to the long slot and cut substantially concentric with the type, for the purpose specified.

10. In a type-writing machine, the combination with a segment having radial slots, of a set of type-carrying bars guided in the slots

and mounted on a curved pivot-wire; each type-bar having an open slot whereby it is detachably engaged to said pivot-wire; the wire-engaging portion of the slot being cut substantially concentric with the type, for the purpose specified.

WILLIAM F. HELMOND.
